UNITED STATES PATENT OFFICE

JOHN V. STEWART, OF JOHNSTOWN, PENNSYLVANIA

CARSTOP

Application filed April 27, 1931. Serial No. 523,298.

My invention relates to stops for railroad cars, and particularly to an improvement on the type applicable to a rail, and transmitting car stopping shocks to one of the rail supporting ties.

Such a stop ordinarily has a depending end part contacting the tie, the other end being bolted to the rail to keep the stop from tilting when struck by a car wheel. Being quite immovable along the rail, this latter end subjects the stop to a severe stress for which it is not designed, as it prevents stopping shocks from being properly transmitted to the tie thru the depending end in the manner intended. Frequent breakage of the stop consequently results from this condition.

It is my intention to provide a stop of the general character just described, which may be fixed down on the rail to prevent tilting, but which will properly transmit stopping shocks to the tie, the consequential breakage being thereby diminished. I further intend to provide a stop that may be simply and inexpensively made, and is of a generally improved character.

In the drawings:

Figure 1 is a specific example of a wheel-stop constructed in accordance with my invention, and applied to a railroad rail.

Figure 2 is a cross section on the line II-II of Figure 1.

Figure 3, a cross section on the line III-III of Figure 1.

These drawings show a railroad rail A, supported by the usual ties B, and straddled by a car-stop C. This car-stop includes an arcuate wheel engaging portion 4, and a pair of depending apertured abutments 5, the latter being positioned against one of the ties B, and preferably fastened thereto by spikes 6.

To prevent the stop from tilting up when struck by a car wheel, it is firmly clamped to the rail A by means of an inverted U-bolt 7, the ends of this bolt extending up each side of the rail, and thru a pair of apertured lugs 8, which straddle the rail, and are formed in the base of the stop, where it is secured by nuts 9. The crossbar of the U-bolt 7 carries a revoluble bearing sleeve 10 which contacts the bottom of the rail A.

The car-stop C also includes a pair of opposed lateral guideways 12, positioned directly beneath the bolt receiving apertures 8, and each carrying a guide plate 13 having an aperture 14. These guide plates 13 extend inward to contact the web of the rail A, the ends of the U-bolt 7 passing thru the aperture 14 in each to retain it in position.

In use, such a car-stop is placed on a rail, with its abutments contacting one of the rail supporting ties, spikes preferably then being driven into this tie thru the holes in the abutments to insure a vertical position of the stop. Then the guide plates are slid into the guideways in the stop, and the U-bolt is inserted, so that the revoluble sleeve it carries bears against the bottom of the rail, and its ends pass up thru the apertures in the guide plates and the apertures in the stop, so that, upon screwing the nuts on these ends, the stop will be firmly clamped to the rail.

By means of this construction the car-stop may be firmly clamped to a rail so as not to tilt up when stopping a car, yet, because of the anti-friction element, it will be able to transmit the stopping shock to one of the ties in the manner it should. This will avoid any breakage because of the shock being taken up by the car-stop in an improper manner. The guide plates will contact the web of the rail to prevent sidewise movement of the stop, and possible deformation of the U-bolt.

While I have shown and described one specific form of my invention it will be understood that I do not wish to be limited thereto, since various modifications may be made without departing from the scope of my invention, as defined in the appended claims.

I claim:

1. A car-stop comprising a body constructed for application to a railroad rail so as to stop a wheel rolling thereon and to transmit the stopping shock to one of the rail supporting ties, and an inverted U-shaped bolt arranged under the bottom of the rail to which the wheel stop is applied and with its ends extending up on each side thereof to engage said body, the crossbar of said U-shaped bolt being provided with

a revoluble member bearing on the bottom of the rail.

2. A car-stop comprising a body constructed for application to a railroad rail so as to stop a wheel rolling thereon and to transmit the stopping shock to one of the rail supporting ties, said body having a pair of apertured lugs straddling the rail to which it is applied, a pair of opposed lateral guideways beneath said apertures, an apertured guide member in each of said guideways so as to contact the web of the rail, and an inverted U-bolt arranged under the bottom of the rail with its ends extending up on each side thereof and thru the apertures in said guide members and the apertures in said body.

3. A car-stop comprising a body constructed for application to a railroad rail so as to stop a wheel rolling thereon and to transmit the stopping shock to one of the rail supporting ties, said body having a pair of apertured lugs straddling the rail to which it is applied, a pair of opposed lateral guideways beneath said apertures, an apertured guide member in each of said guideways so as to contact the web of the rail, an inverted U-bolt arranged under the bottom of the rail with its ends extending up on each side thereof thru the apertures in said guide members and the apertures in said body, and a revoluble bearing member carried by the crossbar of said U-bolt and contacting the bottom of the rail.

35 In testimony whereof, I have hereunto set my hand.

JOHN V. STEWART.
